UNITED STATES PATENT OFFICE

2,543,186

APPARATUS FOR DECORATING POTTERY WARE

William J. Miller, Swissvale, Pa., assignor to Miller Pottery Engineering Company, Swissvale, Pa., a corporation of Pennsylvania

Original application January 8, 1943, Serial No. 471,704. Divided and this application September 12, 1944, Serial No. 553,783

7 Claims. (Cl. 41—1)

1

This is a divisional of my co-pending application S. N. 471,704 filed January 8, 1943, Patent No. 2,407,321.

This invention relates to methods and apparatus for decorating pottery ware. It has to do particularly with the manufacture of ware such as jiggered dinnerware, for instance, plates, cups and saucers, bowls and the like.

The mass production of pottery ware by automatic machine and processes has involved a certain amount of manual intervention, particularly in the treatment and preparation of raw materials and in certain phases of clay, ware and mold transportation, manipulation and processing.

One of the objects of this invention is to place the manufacture of pottery ware on as near a fully automatic basis as possible all the way from the raw material stage to that of dried product ready for first firing. By substantially eliminating the human element in this respect, it is possible to remove handicaps which have heretofore interfered with the continuity, quality and rate of production.

Another and perhaps more important object of this invention is to provide for making simultaneously several different kinds of ware, that is to say, ware having differences in shape, size, decorative pattern or material and even composition by means of a single, unitary mechanical organization. This invention comprehends machinery capable of performing many and different steps, and combinations of steps in the manufacture of pottery ware some of which are conventional steps or operations and others of which afford new and improved ways and means of making pottery ware of this class.

The machinery of the present invention is so constructed and arranged that different sequences of operations may be performed at the same time and variations in the sequences and procedural steps may be made at will and in some cases while the machinery is in operation. Thus, insofar as production diversification is concerned, it may be varied from one which is highly diversified to one wherein substantially little or no diversification occurs. Thus, I provide in a single unitary installation the means of meeting the daily requirements of the average pottery whether it be for large or small amounts of pottery of given shape or design and it is well known that these requirements may vary widely, particularly if the pottery merchandizes a large number of shapes and designs.

Instead of the intermittent fabricating system as illustrated in the patent to Miller No. 2,046,525,

2

I propose to make the present system continuous, somewhat as shown in the application to William J. Miller, Serial No. 413,734, filed October 6, 1941, now Patent No. 2,409,172. That is to say, from the beginning of fabricating operations to the point when the ware is removed from the dryer and therebeyond, the materials will move in continuous fashion whilst the various fabricating operations are performed. This makes for increased production speeds and raises the capacity of the machinery. Furthermore, clay is supplied to the fabricating portion of the present mechanical organization by a system and apparatus disclosed in application Serial No. 454,716 filed August 13, 1942 to William J. Miller, now Patent No. 2,413,330.

In the drawings:

Figs. 1, 2 and 3 taken together to match end to end in their order lengthwise from left to right constitute a diagrammatic view in plan of the entire ware production system of the invention.

Fig. 4 is a view partly in elevation and partly in section of one of the rotary decorating machines of the system employed to either decorate the ware directly or through intermediation of the molds.

Fig. 5 is a plan section of the decorating machine, as taken on the irregular section line 5—5 of Fig. 4.

Fig. 6 is a detail plan section taken substantially on the section line 6—6 of Fig. 4.

Fig. 7 is a detail plan section taken on the section line 7—7 of Fig. 4.

Fig. 8 is a detail front elevation of one of the decorating organizations of the machine of Fig. 4.

Fig. 9 is an enlarged detail view of a mutilated gear and rack assembly seen in Fig. 4.

Fig. 10 is an enlarged detail plan section taken substantially on the section line 10—10 of Fig. 8, with certain parts in changed position.

Fig. 11 is an enlarged detail plan section taken on the section line 11—11 of Fig. 4, illustrating one of the pump units employed.

Fig. 12 is an enlarged fragmentary sectional view of a number of associated ware decorating parts seen in Fig. 4 with said parts brought closer together than seen in said figure.

Figs. 13, 14, 15, 16 and 17 are views illustrating modified forms of the parts seen in Fig. 12 for producing various decorative patterns or formations on the ware directly or indirectly through the molds.

Fig. 18 is a fragmentary sectional view of a piece of ware decorated by the parts seen in Fig. 12.

3

Fig. 19 is a fragmentary sectional view of a piece of ware decorated by the parts seen in Fig. 13.

Fig. 20 is a fragmentary view of a piece of ware decorated by the parts seen in Fig. 16.

Fig. 21 is a fragmentary view of a piece of ware decorated by the parts seen in Fig. 15.

As illustrated diagrammatically in Figs. 1 to 3, the system includes an endless flexible mold conveyor 51 comprising a series of centrally open 10 mold carriers or positioning rings 52 interconnected in equally spaced relation by flexible links or cable sections 53. The conveyor is maintained in a substantially horizontal plane while traveling continuously in a tortuous path about idler 15 sprockets and rotary machines of the system by having outboard supporting rollers 54 riding on rails 55.

The molds for forming four types of ware are carried in the rings 52 in duplicate successive sets which, in the course of the conveyor, are brought into co-operative relation with a series of rotary machines 60, 61, 62, 63 and 64 designed to respectively condition the molds, treat molds for a certain method of ware decoration, treat molds for another method of ware decoration, further condition the treated molds and treat molds for engobing certain ware. These machines are selectively used.

The molds then continue to a series of rotary machines 65, 66 and 67 designed to selectively feed clay charges of similar or of different composition or conditioned clay bodies to the molds and puddle and partially form the charges comparatively with respect to the ware forming surfaces of the molds prior to feeding. The charge feeding machines may be supplied from an enclosed clay preparation organization, designated for purposes of location by the letter R, Fig. 1, this organization being designed to simultaneously and continuously prepare the various clay bodies desired from the various plastic and non-plastic materials required and selectively feed same to the machines.

After receiving the charges, the molds continue to a series of rotary machines 71 to 93 inclusive, designed to selectively perform various forming, conditioning and decorating operations to produce the ware.

The molds then pass through a drier 95 for an optimum period to dry to leather hardness certain ware to be appendaged, such as cups or the like, which are then conveyed out of the drier at a take-off station E to a rotary machine 96 which transfers same from an upright position in the molds to an inverted position in co-operative relation with an appendaging machine 97, the transfer machine also being designed to fettle and smooth the ware prior to being transferred.

The molds are then returned into the drier and are conveyed past take-off stations F and G located along the conveyor course and are brought at predetermined points into co-operative relation, respectively, with rotary machines 98 and 99 designed to transfer other types of ware, each requiring a different drying period, to suitable conveying apparatus 100 and 101 arranged to convey the ware to suitable locations for further treatment. These machines are also designed to fettle, smooth and reverse or reposition the ware incident to transferring same, if desired.

Upon leaving the drier, the molds are advanced to a rotary machine 102 employed to lay to the molds or reform thereon partly dried ware that may have become slightly distorted during drying

and being especially of use as located, in an installation or an adaptation of the system wherein no type of ware is completely dried in the dryer. However, if the system is adjusted so that the 5 ware leaving the dryer is too dry for the reforming operation, said machine 102 or number of same may be disposed along the conveyor course adjacent one or each of the take-off or transfer stations E, G, and F.

From the reforming machine 102, the molds continue to another rotary transfer machine 103 co-operating with a conveying system 103a to transfer the various types of ware that may remain on the conveyor to any one or a number of selected locations for further treatment, the machine being designed to fettle and smooth the ware and reverse the position thereof if desired.

Upon leaving the transfer machine 103, the empty molds are advanced to a rotary machine 104 co-operating with a conveying system 104a to remove any one or all the molds of each set and transfer same to a suitable location for storage when changing the system over to the production of a different type or types of ware, or 20 when damaged or worn molds require replacement for repair.

The next machine 105 along the course of the conveyor is also of the rotary type designed to co-operate with a conveying system 105a for transferring molds for a certain type or types of ware from one or more storage locations and placing same in the emptied mold carriers in any desired order.

The molds then continue to a rotary conditioning machine 106 designed to remove any foreign matter from the molds, and then continue to another conditioning machine 107 employed to apply to all the molds, or only those which have just been placed on the conveyor, a conditioning 35 medium, such as oil. The molds then pass through a conditioning zone 108 comprising a tunnel within which the air is suitably heated or otherwise conditioned to dry or otherwise put the molds in a proper condition as they return to complete another cycle of operation.

Generally, the machines are of the rotary table type, about the tables of which the conveyor meshes to remain in co-operative relation with each machine during a sufficient portion of its rotation to perform the various operations on the molds or ware.

As seen in Figs. 2 and 3, a power unit 109, such as a combination motor and adjustable speed reducer is employed to constantly drive the machines and mold conveyor in synchronism, through a power shaft 109a and suitable gearing 109b co-operating between same and the rotary machines 72, 81, 83 and 93 which thus serve as driving connections for the conveyor at spaced 55 intervals therealong and whereby the conveyor in turn serves as a driven connection for the rotary machines with which it meshes between said intervals. It is also contemplated that the conveyor and any number or all of the said rotary machines and idlers defining its course may be independently or collectively driven in timed relation.

Of the various methods to be employed in decorating the ware, one is to apply the decorating medium to the mold to be transferred to the ware as it is formed thereon. Another method is to apply the decorating medium directly to the ware either immediately or during a predetermined time after jiggling or before or after it 70 has been fired. Then again, the medium may

be a dye or enamel or the like, or it may be colored clay applied to the ware to form inlaid or incrusted or embossed ornamental formations, or it may be impressed into the green ware with or without a coloring medium application.

Therefore, the machine 61 to which the molds are advanced after leaving the mold conditioning machine, has been designed for use in carrying out these various decorating methods, but is illustrated in Figures 4 to 13 as being adapted to apply, for instance, inlaid or relief ornamental clay formations on a piece of ware 169, as seen in Figures 18 to 21, inclusive.

To this end, the machine includes a base 170 of a pedestal 171 supporting the lower end of a central hollow shaft 172 on which rotates a turret 173 having equally spaced thereabout pockets 174 and sheave formations 175 therebetween to respectively receive the carriers and cable sections of the conveyor as it meshes to an optimum degree therearound.

After the mold carriers are positioned in the pockets of the table, each mold is elevated from its carrier by a vertically reciprocable chuck 175a and brought into register with a decorating device 176, which then reciprocates into contact with the mold surface and applies the ornamental clay formations 168 thereon (Fig. 12), the device remaining in contact with the mold a sufficient period to insure proper application before it is raised to clear the mold and before the mold is lowered by the chuck into the carrier and carried from the machine.

As seen in Figs. 10 and 12 each decorating device, for hollow or flat ware, comprises a hollow head formed by a base portion 177 and a platen member 178 detachably secured to the base by bolts 178a and comparatively formed with respect to the ware forming surface of the mold it cooperates with. Mounted in openings in the platen face, for replacement, are decorating inserts 178b having molding recesses 179 from which the colored clay ornaments are deposited on the surfaces of the mold when the platen contacts same (see Fig. 12). Thus when the ware has been formed on the mold, said ornaments are inlaid in the normally visible surface or side of the ware, especially flat ware, such as plates as seen in Fig. 18. The inserts of each platen are made of permeable material and, as it contacts the mold surface, air under pressure is forced therethrough to release the clay ornaments from the recesses and apply them to the mold. Also, the surfaces of the molds may be suitably treated by the machine 61 to cause the ornaments to adhere thereto, at least temporarily after application.

When each decorating device 176 is raised to its uppermost limit, its position is reversed during the intermediate portion of its stroke to bring its platen into operative relation with a matrix device 180 which supplies charges of variously colored clays to the recesses of the platen. For this purpose, on the table 173 is a concentric supporting drum 181 having spaced thereabout four vertical guideways, each formed by guide bars 182 between which is guided for vertical reciprocation, a crosshead 183. Each crosshead has a pair of lateral arms 184 with bearings 185 rotatably supporting a horizontal shaft 186 on which is a hollow supporting head 187 carrying one of the decorating devices 176. The base of each decorating device has a threaded central boss 188 threaded on a threaded stem 189 of its support head for adjustment with respect to

molds, with a lock nut 189a arranged on the stem to hold the device in adjusted positions.

During the intermediate portion of the stroke of each crosshead 183, the shaft 186 carried thereby is rotated 180 degrees to reverse the decorating device, by said shaft having a mutilated gear 190 co-operating with a rack 191 on a bracket 192 of the drum 181 (Figs. 4, 9 and 10). To hold the decorating device in reversed positions during the end portions of its stroke so that its platen engages and disengages the mold and matrix in alignment and clears same before being reversed, the shaft 186 has a square cam 193 arranged to have sliding engagement with guides 194 at the ends of the rack 191.

Arranged in the drum and secured to the central shaft 172 is a grooved cam 195 for co-operating with rollers 196 on the crossheads to reciprocate same in proper timed relation with the conveyor to effect the decorating operation.

As seen in Figs. 4 and 12, each matrix device 180 comprises a hollow head formed by a base 200 and a matrix member 202 detachably secured to the base by bolts 202a and formed comparatively with the platen of its associated decorating device to cover same when engaged thereby. Each matrix head is mounted on a bracket 201 of the drum 181 for adjustment with respect to its associated platen, by its base 202 having an upright threaded stem 202c adjustably held in a bearing 202d of the bracket by nuts 202e. Detachably secured in bored cut portions 202b in the matrix face are molding members or inserts 203 for co-operating with the inserts 178b of the platen 178 to mold the ornamentations, the molding members having ports 203a of small diameter from which the colored or natural clay is fed to the molding cavities formed between same and the said platen inserts when engaged thereby.

Incident to filling of the recesses in the platen, and while the platen is lowered into contact with the mold, the decorating head 176 is vacuumized to hold the clay charges in the recesses of the platen inserts before air under pressure is admitted into the head to release the charges when contacting the mold. To this end, as each decorating head moves toward and engages the mold, it is connected successively with a vacuum line 205 and an air pressure line 206 by way of a combination distributor and valve device 207, on the shaft 172, a flexible conduit 208 leading therefrom, a passage 209 in each crosshead leading to an annular passage-way 210 formed between one of the crosshead bearings 185 and the supporting head 187 and passage-ways 211 and 212 formed in said head and the stem 189 thereof (see Figs. 4, 5 and 10).

To further insure retention of the clay charges in the recesses 179 of the platen inserts while the platen is in motion, clay anchoring formations 179a may be provided in or on the bottom wall of the recesses, as seen in Fig. 12.

The ports 203a of the molding members 202 may be selectively supplied from any one of a series of differently colored clay supply lines 215, 216 and 217 by way of valved branches 218 of each line leading to headers 219 of conduits 220, 221 and 222, distributors 223 on the central shaft 172 co-operating with the conduits respectively, piping 224 connecting with the ports through passage-ways 224a in the matrix base 200, nozzles 224b on the matrix member 202 extending in the bores 202b into connection with said ports, and pumps 225 interposed in the piping.

The pumps 225 are of the cylinder and adjustable stroke piston type arranged in sets on the drum 181 for their respective matrix heads, each set being operated simultaneously at the proper time, to feed a predetermined volume of clay, by a normally stationary cam 226 on the central shaft through spring-pressed levers 227 connecting with the pump pistons. To regulate the capacity of each pump in accordance with that required for the ornamentations, each pump (see Fig. 11) has a piston rod extension 228 extending through an end wall bearing 229 of the pump cylinder with an adjustable stop or nut 230 threaded thereon to engage the bearing in determining the return stroke limit of the piston.

The molding inserts 203 of the matrices may be of permeable material and incident to discharge of clay from the ports 203a thereof, air under pressure may be forced therethrough to eject the charges therefrom by the annular space of the bores 202b formed over said inserts being connected with the air-pressure line 206 by way of a combination distributor and valve 231 on the central shaft, a flexible conduit 232 leading therefrom into connection with the chamber 232a in the matrix head and passages 232b connecting the chamber with the bore portions 202b.

Each of the colored clay supply lines 215, 216 and 217 may supply the same or a different type of clay supplied thereto by the clay preparation system R, with each line having interposed therein a coloring device 235 to color the clay as it passes therethrough. In this way, the ornamental clay designs applied to the various types of ware may be of the same composition or character as that of the body of the ware so that the drying and firing behavior of both will be the same.

If it is desired to decorate the ware by applying different colored clay incrustated ornamentations in relief, as seen at 236, Fig. 19, same may be produced by forming suitable molding recesses 231 in the molding surfaces of the molds (Fig. 13) and providing the molding inserts 203 of the matrices therefor with corresponding recesses 238 from which the charges are transferred by the associated decorating head 176.

Before the molds are raised off the conveyor carriers by the chucks 175a, they are rotated in the carriers by the chucks into a predetermined angular position with respect to the platens, so that any selected surface formations thereof adapted to receive the charges from the recesses 179 of the platen inserts, such as the recesses 237, may be brought into co-operative alignment therewith. By so spotting the molds eliminates the necessity of their being carried in the carriers in a predetermined angular position.

For this purpose, each chuck 175a, Figure 4, is mounted on the top end of a vertical shaft 175b reciprocable within and in sliding key connection with a sleeve 175c rotatably mounted in a bearing 175d of a wheel 175e on the central shaft 172 and connected with the table 173 thereabove. The shaft 175b is reciprocated to raise and lower the chuck by a lever 175f actuated by a stationary cam 175g on the central shaft 172. On the cam is a cam dwell portion 175h which causes the chuck to temporarily halt intermediate its lowered and raised positions when elevated. While the chuck is halted, it is rotated by the sleeve 175c a predetermined amount, to at least complete one revolution, whereby the chuck is caused to be connected with the mold by a spring-pressed key or detent 175i in the its upper edge arranged to

snap into a notch 175j formed in an annular surface 175k of the mold, upon which surface the detent slides in a depressed position before snapping into the notch and causing the mold to rotate with the chuck into its predetermined angular position before its final upward movement into co-operative relation with the platen (see Fig. 12). After the chuck returns the mold to the carrier, when lowered it is rotated in a reverse direction to its original position by the sleeve preparatory to another cycle of operation. Each sleeve 175c is oscillated or rotated in opposite directions at the proper time by a cylinder and piston fluid-pressure motor 175m carried on the wheel 175e,

and on whose piston rod 175n is a rack gear 175o guided in a guideway 175p of the bearing 175d and co-operating with a gear 175q on the sleeve to oscillate same upon reciprocation of the piston (see Fig. 6). To regulate the angular position to which the molds are rotated by the chucks, each piston rod 175n has an abutment 175r arranged to engage an adjustable stop or screw 175s threaded in a lug of the bearing 175d to limit the forward stroke of the rack gear 175o.

Each fluid motor 175m is energized at the proper time from the air-pressure line 206 through a distributor 206a and a four-way valve 206b operated by adjustable arms 206c on the central shaft and connected with both ends of the motor cylinder by valved conduits 206d to regulate the phase and speed of oscillation of the chuck.

Each shaft 175b may have a central duct 206e opening into the chuck thereon and connected with the vacuum line 205 through a combination distributor and valve 206f and, similar in construction to that shown in Figure 7, flexible conduit 206g, to vacuumize the chuck to hold the mold therein after same has been angularly positioned by the chuck.

The machine 62 to which the molds are next advanced may be another decorating machine in carrying out the printing method of decorating wherein ceramic pigment, colored paint or other printing media are employed.

This machine may constitute a duplicate of the machine 61 wherein the platens 178 would be adapted to print the ornamentations on the molds from suitably formed pads or cuts 240 provided on decorating inserts 240a detachably secured in the openings of the platen (see Fig. 17). These pads may be inked by their associated matrix 202 from permeable pads 241 on inking inserts 241a detachably secured in the bores 202b in the matrix face and having a passage or passages 241b therein co-operating between the pad and the associated nozzle 203 (Fig. 12) in the bore whereby the pad may be constantly or intermittently supplied a measured amount of the printing medium from a pump 225. In this case, the supply lines 215, 216 and 217 (Fig. 4) would be selectively connected with sources of supply of variously colored printing media, instead of the clay preparation system.

While Fig. 17 illustrates the printing apparatus adapted to print on a plain mold surface, in imparting a plain printed design or adornment to the ware when formed thereon, Fig. 16 illustrates an adaptation of the apparatus for applying the printing medium to a decorating formation 237 of the mold, in producing ware with an integral embossed decorating formation 237a (Fig. 20) adorned with a colored coating, which coating may be colored clay or any other coating medium. This also applies to the production of ware having

recessed decorative formations, as seen at 237b, Fig. 21.

The machine 63 to which the molds are next advanced, is provided to condition the decorations applied by the machines 61 and 62. Such conditioning may comprise applying a liquid bonding medium and/or a fluid drying medium to the decorations, such as hot air under pressure, to at least partially harden same sufficiently to withstand forming of the ware thereover. For this purpose, this machine may comprise a duplicate of the machine 60, as seen in Fig. 1, with the supply lines 148 and 151 thereof supplying the desired media for different types of decorations.

The molds are then advanced to the machines 64 arranged to further treat certain molds in producing engobed ware with the decorations over the engobing, which may comprise a thin clay coating of a desired color over the ware to enhance the appearance thereof. For this purpose, said machine may comprise another duplicate of the machine 60 (Fig. 1) with the supply lines 148 to 151 supplying the variously colored fluid engobing medium or clay slips of the same of different compositions from the clay preparation system R and whereby said medium would be sprayed over the molding surfaces and decorations thereon to be transferred to the ware when formed thereon.

Having thus described my invention, what I claim is:

1. In combination with a continuously movable mold-carrying conveyor provided with mold carriers, apparatus for applying a fluid ware-surfacing medium to molds carried by the conveyor comprising a rotatable support provided with spaced pockets for receiving said carriers, a medium applicator carried by said support above and in vertical alignment with each of said pockets, a medium feeder carried by said support above and in vertical alignment with each of said applicators, means for moving said applicators and feeders one toward the other for transferring a supply of said medium from the feeders to the applicators, means for moving said applicators and said molds one toward the other for depositing said supply on said molds, and mechanism for synchronously and continuously moving said conveyor and rotatable support.

2. In combination with a continuously movable mold-carrying conveyor provided with mold carriers, apparatus for applying a fluid ware-surfacing medium to molds carried by the conveyor comprising a rotatable support provided with spaced pockets for receiving said carriers, a vertically reciprocable medium applicator carried by said support above and in vertical alignment with each of said pockets, a medium feeder carried by said support above and in vertical alignment with each of said applicators, means carried by said support for moving said applicators up to said feeders for transferring a supply of said medium from the feeders to the applicators and for moving said applicators downwardly toward said molds for depositing said supply on said molds, and mechanism for synchronously and continuously moving said conveyor and rotatable support.

3. In combination with a continuously movable mold-carrying conveyor provided with mold carriers, apparatus for applying a fluid ware-surfacing medium to molds carried by the conveyor comprising a rotatable support provided with spaced pockets for receiving said carriers, a ver-

tically reciprocable medium applicator carried by said support above and in vertical alignment with each of said pockets, a medium feeder carried by said support above and in vertical alignment with each of said applicators, means carried by said support for moving said applicators up to said feeders for transferring a supply of said medium from the feeders to the applicators and for moving said applicators downwardly toward said molds for depositing said supply on said molds, mechanism for rotating said applicators on a horizontal axis during their upward and downward movements to bring their medium receiving surfaces into contact with said feeders and with said molds respectively, and mechanism for synchronously and continuously moving said conveyor and rotatable support.

4. In combination with a continuously movable mold-carrying conveyor provided with mold carriers, apparatus for applying a fluid ware-surfacing medium to molds carried by the conveyor comprising a rotatable support provided with spaced pockets for receiving said carriers, a medium applicator carried by said support above and in vertical alignment with each of said pockets, a medium feeder carried by said support above and in vertical alignment with each of said applicators, means carried by said support below said pockets for lifting said molds upwardly into a medium applying position, means for moving said applicators and feeders one toward the other for transferring a supply of said medium from the feeders to the applicators, means for moving said applicators downwardly into said medium applying position for depositing said supply on said molds, and mechanism for synchronously and continuously moving said conveyor and rotatable support.

5. In combination with a continuously movable mold-carrying conveyor provided with mold carriers, apparatus for applying a fluid ware-surfacing medium to molds carried by the conveyor comprising a rotatable support provided with spaced pockets for receiving said carriers, a vertically reciprocable medium applicator carried by said support above and in vertical alignment with each of said pockets, a medium feeder carried by said support above and in vertical alignment with each of said applicators, means carried by said support for moving said applicators up to said feeders for transferring a supply of said medium from the feeders to the applicators and for moving said applicators downwardly toward said molds for depositing said supply on said molds, mechanism for rotating said applicators on a horizontal axis during their upward and downward movements to bring their medium receiving surfaces into contact with said feeders and with said molds respectively, vacuum means associated with each of said applicators for holding said medium supply on the applicators during said downward movement, and mechanism for synchronously and continuously moving said conveyor and rotatable support.

6. In combination with a continuously movable mold-carrying conveyor provided with mold carriers, apparatus for applying a fluid ware-surfacing medium to molds carried by the conveyor comprising a rotatable support provided with spaced pockets for receiving said carriers, a medium applicator carried by said support above and in vertical alignment with each of said pockets, a medium feeder carried by said

11

support above and in vertical alignment with each of said applicators, means carried by said support below said pockets for lifting said molds upwardly into a medium applying position, means for rotating said mold lifting means on their vertical axes an amount sufficient to place desired surfaces of the molds in position to receive said medium applications, means for moving said applicators and feeders one toward the other for transferring a supply of said medium from the feeders to the applicators, means for moving said applicators downwardly into said medium applying position for depositing said supply on said molds, and mechanism for synchronously and continuously moving said conveyor and rotatable support.

7. In combination with a continuously movable mold-carrying conveyor provided with mold carriers, apparatus for applying a fluid ware-surfacing medium to molds carried by the conveyor comprising a rotatable support provided with spaced pockets for receiving said carriers, a vertically reciprocable medium applicator carried by said support above and in vertical alignment with each of said pockets, a medium feeder carried by said support above and in vertical

5
10

alignment with each of said applicators, means carried by said support below said pockets for lifting said molds upwardly into a medium applying position, means carried by said support for moving said applicators up to said feeders for transferring a supply of said medium from the feeders to the applicators and for moving said applicators downwardly toward said molds for depositing said supply on said molds, and mechanism for synchronously and continuously moving said conveyor and rotatable support.

WILLIAM J. MILLER.
